UNITED STATES PATENT OFFICE.

JOSHUA B. BARNES, OF SPRINGFIELD, ILLINOIS.

DESIGN FOR A THIMBLE FOR STAY-BOLTS FOR BOILER-SHEETS.

SPECIFICATION forming part of Design No. 34,836, dated July 23, 1901.

Application filed June 8, 1901. Serial No. 63,801. Term of patent 14 years.

To all whom it may concern:

Be it known that I, JOSHUA B. BARNES, of Springfield, Sangamon county, Illinois, have invented and produced a new and original Design for a Thimble for a Stay-Bolt for Boiler-Sheets, of which the following is a specification.

In the drawings, Figure 1 is a side elevation; Fig. 2, a sectional view; Fig. 3, a plan view; Fig. 4, a bottom view.

The leading feature of my invention is in the tapering form of the thimble inside and out throughout its threaded portion. Below this threaded portion the lower end of the thimble is reduced in diameter, while with-

in, below the threaded portion, the bore is rounded and contracted to a central opening which has unthreaded walls. The exterior tapering threaded portion is shown at *a*, the interior at *b*, the reduced lower unthreaded portion of the thimble at *c*, the rounded interior at *d*, and the central opening at *e*.

What I claim is—

The design for a thimble for a stay-bolt for boiler-sheets as herein shown and described. 25

JOSHUA B. BARNES.
